CLAIM

The ornamental design for a table riser with drawer, as shown and described.

DESCRIPTION

FIG. 1 is a top perspective view of a table riser with drawer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom and left perspective view of the left legs of the table riser with drawer shown separately for ease of illustration;

FIG. 9 is a bottom and left perspective view of the other legs thereof;

FIG. 10 is a bottom and left perspective view of a table top of the table riser with drawer; and,

FIG. 11 is an exploded bottom and left perspective view of the table riser without the drawer.

The broken line portions of the table riser with drawer in FIGS. 1-11 represent unclaimed portions of the claimed design and form no part thereof.
